United States Patent Office

Des. 209,252
Patented Nov. 14, 1967

209,252

AIRCRAFT

Robert E. Foote, 1030 Shadow Wood,
Lewisville, Tex. 75067

Filed Sept. 12, 1966, Ser. No. 3,828

Term of patent 14 years

(Cl. D71—1)

FIG. 2

FIG. 3

FIG. 1

FIG. 5

FIG. 6

FIG. 4

FIG. 1 is a perspective view of the aircraft, showing one embodiment thereof;

FIG. 2 is a plan view of the aircraft of FIG. 1;

FIG. 3 is a side view of the aircraft of FIG. 1;

FIG. 4 is a perspective view of the aircraft, showing the second embodiment thereof;

FIG. 5 is a plan view of the aircraft shown in FIG. 4; and

FIG. 6 is a side view of the aircraft shown in FIG. 4. The fragmented showing of the rotor blades in FIGURES 1, 2, 4, and 5 is for convenience of illustration only.

I claim:

The ornamental design for an aircraft, as shown and described.
